JOHN JENSEN, OF ROCKFORD, ILLINOIS, ASSIGNOR TO WHITNEY METAL TOOL COMPANY, OF ROCKFORD, ILLINOIS, A CORPORATION OF ILLINOIS

FOOT PRESS

Application filed June 29, 1931. Serial No. 547,586.

The invention pertains to a tool or punch press for use in performing, shaping or forming, and allied operations, and especially adapted for operation by a foot lever.

5 The object of the invention is to provide a tool of the character set forth, which is simple in construction so as to be capable of economical manufacture, easily operable, and adapted for accurate manipulation.

10 A preferred embodiment of the invention is illustrated in the accompanying drawing forming part hereof, in which:

Figure 1 is a fragmentary, vertical sectional view through the improved press, certain of the parts being shown in elevation.

15 Fig. 2 is an end view looking from the right in Fig. 1.

The tool comprises, as herein shown, a frame having a base plate 7 from the rear portion of which rises a standard 8 carrying an overhanging arm 9, the several parts of the frame being preferably cast integral. The base plate 7 is in the present embodiment adapted to be mounted upon a bench or table 25 top 10 having a slot 11 therein through which a portion 12 of the frame depends.

In the forward end of the overhanging arm 9 is mounted a movable tool-carrying slide in the form of a block 13. The latter is 30 vertically slidable between opposed portions 14 of the frame providing suitable guideways. At its lower end the slide 13 is suitably constructed to receive and hold a desired tool (not shown) according to the purpose 35 for which the press is to be used.

Extending generally in a front to rear direction relative to the overhanging arm 9 is an operating lever 14 fulcrumed at its forward end on a pivot pin 15 mounted in opposed walls of the arm 9, the latter being 40 made hollow at its forward end for the purpose of receiving and enclosing the lever. The pivot pin 15 is located closely adjacent the tool slide 13, and the forward end of the lever passes through an opening 16 in the forward end of the arm and into a slot 17 in the tool slide. The upper and lower edges of the forward end portion of the lever are rounded 45 and engage with the tool slide through the medium of upper and lower wear plates 18

which are removably secured in place by means of a front plate 19. The latter as herein shown is secured in position by means of a screw 20 entered through a slot 21 in the upper end of the plate and anchored in the 55 slide. The lower end of the plate is notched to receive a retaining screw 22.

The lever 14 is made of substantial length so that its rear end projects from the rear end of the arm 19 for pivotal connection with 60 the upper end of a link 23. The lower end of said link 23 is pivotally connected through the medium of a pivot pin 24 with the upper end of a second link 25, which in turn is mounted on a pivot pin 26 carried by the upper end of a support 27. The latter is preferably in the form of a screw capable of being raised or lowered by means of a threaded collar 28 bearing on top of the rear end of the frame. By means of the adjustable pivot 70 pin 26, the range of movement of the tool slide 13 may be varied. Primarily, however, the variable support affords a means for adjusting the links 23 and 25 to assume any desired position when the tool slide 13 is at 75 the end of its downward stroke as determined by the operation to be performed on any particular work piece. A set screw 29 serves to fasten the screw in the base.

It will be observed that the links 23 and 80 25 constitute a toggle linkage operable between the base plate 7 and the rear end of the lever 14. For actuation of such linkage I employ an upright lever 30 of substantial length, fulcrumed in the depending portion 85 12 of the frame on a pivot pin 31 and having its upper end pivotally connected by means of a link 32, with the pivot pin 24 constituting the intermediate pivot of the toggle. The lower end of the lever 30 is constructed 90 so as to be conveniently operable by the foot of an operator positioned forwardly of the tool. Herein I have shown for this purpose a transverse foot bar 33.

While the screw 27 is capable of adjustment to vary the range of movement of the tool slide, the various pivotal connections between this screw and the slide render this form of adjustment unreliable as an accurate means for limiting the downward travel of 100

the slide. I therefore have provided an adjustable stop in the form of a screw 34 mounted in the overhanging arm 9 in position to be engaged by the upper edge of the lever 14 at the end of a predetermined downward movement of the slide. The screw 34 is equipped with a lock nut 35 so that it may be held positively in set position. Such limiting of the downward movement of the tool 10 slide is especially important where the press is employed in performing certain shaping or forming operations. With the downward movement of the tool slide thus limited by the adjustable stop, the desirability of an 15 adjustable pivot pin 26, adapting the links of the toggle means to be adjusted in accordance with the so modified range of movement, becomes apparent.

For coaction with a tool carried by a slide 20 13, an auxiliary tool or die (not shown) may be mounted in a hole 36 provided in the forward end of the base plate 7 beneath the tool slide 13.

It will be observed that the construction 25 provided is of a simple character so that the press may be manufactured economically; that by the use of the toggle linkage in combination with the levers 14 and 30, operations requiring a powerful movement of the forming or punching tool may be accomplished 30 with comparative ease; and that where accuracy is required by the nature of the work being done, the extent of movement of the slide during its operating stroke may be definitely and accurately defined.

I claim as my invention:

A tool of the character set forth, comprising, in combination, a frame having a horizontally disposed arm, a tool slide mounted 40 for up and down movement at the forward end of said arm; a lever operatively engaging said slide and disposed approximately at right angles to the path of movement thereof, said lever having a fulcrum adjacent the 45 end engaging said slide, a toggle linkage having one end connected to the remaining end of said lever and the other end adjustably supported in said frame, a substantially vertical lever fulcrumed on said frame and 50 having a link connection with the intermediate pivot of said toggle linkage to actuate said first mentioned lever, and an adjustable stop positioned to be engaged by said first mentioned lever to limit the downward movement of said tool slide.

In testimony whereof, I have hereunto affixed my signature.

JOHN JENSEN.
